R. OLSON

OPERATING AND LATCH DEVICE FOR DOORS

Filed June 3, 1921

Inventor
Richard Olson,

By *H. Woodward*

Attorney

UNITED STATES PATENT OFFICE.

RICHARD OLSON, OF SUPERIOR, WISCONSIN.

OPERATING AND LATCH DEVICE FOR DOORS.

Application filed June 3, 1921. Serial No. 474,620.

To all whom it may concern:

Be it known that I, RICHARD OLSON, a citizen of the United States, residing at Superior, in the county of Douglas and State of Wisconsin, have invented certain new and useful Improvements in Operating and Latch Devices for Doors, of which the following is a specification.

The invention has for an object to effect improvements in door control apparatus, adaptable to use in the opening and closing of doors, and for holding doors in open position, or closed position. The device is especially useful in connection with double swinging doors, such as doors of garages and other structures.

It is an important aim of the invention to effect improvements in the structural details of such apparatus, the aim being especially to improve that type in which a horizontally sliding element movable in a path aligned with the center of a door is connected by links to respective doors opening outwardly from the path of the sliding member.

Additional objects, advantages and features of invention reside in the construction, arrangement and combination of parts as may be understood from the following description and drawings, in which

Figure 1 is a top view of one embodiment of the invention, with certain supporting structural parts omitted,

Fig. 2 is a detail elevation of the sliding element, its mounting, and means for holding it in open position,

Fig. 3 is a detail of a familiar construction of a spring hinge.

There is illustrated formally, a small building 10, having doors 11 hinged at the sides of the door opening 12, to swing outwardly, their radius being such that they will meet midway of the opening. Upon suitable cross pieces 13 and 14 adjacent the top of the door opening, a guide bar 15 is fixed, at right angles to the plane of the doors when closed and in line with the line upon which they meet. The bar 15 has slideable thereon a sleeve 30, having lateral ears at the side, in which there are pivoted links 18 extending respectively therefrom and pivotally connected to the respective doors 11 adjacent their swinging edges. The links 18 are of a length to connect the doors with the sleeve when the doors are at full open position as illustrated in Fig. 1, and when

the sleeve is at the forward limit of its movement upon the bar 15.

The sleeve is provided with an upstanding arm 31 upon which there is mounted a plain bar lever 32 of the second class, the forward end of which has a cable 33 connected thereto extended downwardly therefrom and thence forwardly under a pulley 34 mounted upon the forward end of the sleeve. The rear end of the sleeve is provided with the vertical guide 35 in which there is slideable a bolt 36 connected by the link 37 with the rear end of the lever. A spring 38 is connected between the lever 32 and the sleeve to hold the bolt 36 yieldingly in engaged position. The bolt is of a length to clear the bar 15 when raised a slight distance, the bar having latch openings 40 both adjacent the rear end and adjacent the forward end, in which the bolt 36 may engage.

In use when the doors are moved into closed position, the bolt 36 will latch in the opening 40 adjacent the rear end of the bar 15, locking the doors in closed position. When it is desired to open the doors, a pull upon the cable 33 will operate the lever 32 withdrawing the bolt 36, and continued force applied to the cable will then move the sleeve 30 forwardly, operating the doors, and moving them to open position. When the parts are thus positioned, release of the cable 33 will permit the bolt 36 to engage in the forward opening 40 of the bar 15 when aligned therewith. It is an especial advantage of this device that it may be operated for opening or closing by the driver of a motor vehicle without the driver leaving the vehicle, by extending the cable 33 to a location convenient for manipulation from the vehicle, and utilizing a spring element to yieldingly close the doors after any familiar method. Ordinary spring hinges may be employed at 41, as indicated in Fig. 1 of the drawings. When operating the mechanism for opening of the doors, by operating the cable to draw the sleeve 30 forwardly so that the bolt 36 is slightly forward of the opening 40 and then quickly releasing the cable, the bolt will spring downwardly and slip into the opening 40 as the doors slowly begin movement toward closed position, checking further movement thereof. When it is desired to close the doors, a like pull upon the cable 33 will withdraw the bolt,

and by slowly reducing the force applied to

the cable, the doors will be permitted to move the slide so that the bolt 36 will pass rearwardly of the opening 40, (it being understood that the force required to hold the latch in released position is less than that necessary to hold the doors open). The cable may then be released, and complete closing of the doors permitted, the bolt automatically latching itself when moved to closed position, as before indicated. If desired, spring devices or weights of familiar form may be used for closing the doors.

What is claimed is:—

1. In a device of the character described, the combination of hinged door elements, means acting to close the doors yieldingly, a rectilinear guide adjacent the swinging edges of and vertical to the plane of the closed doors, a slide thereon, link elements connected to respective doors adjacent their swinging edges and to the slide, spring-pressed holding means to hold the slide at the limits of its movement, and cable operated means to release the holding means extending forwardly from the slide and engaged there-

with whereby draft on the cable will release said holding means, and continued draft on the cable will move the doors toward open position.

2. A hinged door synchronizing and fastening device of the character described comprising a horizontal bar, a sleeve slideable thereon, a vertical bolt guide on the sleeve, a bolt reciprocable therein to engage the bar, said bar having bolt openings therethrough adjacent respective limits of movement of the slide, an arm on the sleeve forwardly of the bolt, a lever on the arm connected at one end to the bolt, an anti-friction guide on the sleeve forwardly of the arm, a cable connected to the forward end of the lever and extended forwardly through said guide, and yielding means to move the bolt to engaged position.

In testimony whereof I have affixed my signature in presence of two witnesses.

RICHARD OLSON.
